UNITED STATES PATENT OFFICE.

ALBERT J. HARMS, OF VICTORIA, ILLINOIS.

SUPPORT FOR RAILWAY-RAILS.

No. 867,362.

Specification of Letters Patent.

Patented Oct. 1, 1907.

Application filed August 17, 1906. Serial No. 330,937.

To all whom it may concern:

Be it known that I, ALBERT J. HARMS, a citizen of the United States, residing at Victoria, in the county of Knox and State of Illinois, have invented certain new and useful Improvements in Supports for Railway-Rails, of which I do declare the following to be a full, clear, and exact description, reference being had to the accompanying drawing, forming part of this specification.

10 The present invention has for its object to provide an improved construction of metallic support for railway rails, the object of the invention being primarily to afford a simple, durable and effective means for holding the rail in position upon the tie and to afford means whereby an insulation of the rail may be effected.

The invention consists in the features of novelty hereinafter described, illustrated in the accompanying drawing and particularly pointed out in the claims at 20 the end of this specification.

The present invention is particularly applicable for use in connection with metallic railway ties, such, for example, as that set forth in Letters Patent No. 697,480, granted to me April 15, 1902, although features of the 25 invention will be found adapted for use in connection with railway ties of other construction.

Figure 1 is a plan view of portions of a railway track having my invention applied thereto, parts being broken away for better illustration. Fig. 2 is a view 30 in vertical section on line 2-2 of Fig. 1. Fig. 3 is a view in vertical section on line 3-3 of Fig. 1. Fig. 4 is a view in vertical section on line 4-4 of Fig. 1. Fig. 5 is a view in vertical section on line 5-5 of Fig. 1. Fig. 6 is a plan view showing a portion of a metallic tie with a modified construction of tie plate, the web of the rail being shown in longitudinal section. Fig. 35 7 is a view in vertical section on line 7-7 of Fig. 6. Fig. 8 is a view in vertical section on line 8-8 of Fig. 6. Fig. 9 is a detail plan view showing a portion of 40 a tie.

The tie A is shown as formed of a T-shaped bar, the broad base a of which is adapted to rest upon the road bed, and the web a' of which is provided with the notched or cut-away spaces a^2 to receive the tie plates 45 whereon the base flanges of the rails rest. In order to afford a broad bearing at the top of the slots or cut-away spaces in the web a' , the metal of the web at such points is expanded as at a^3 so that it extends upon both sides of the web a' , as most clearly seen 50 in Figs. 2 and 9 of the drawing. It will be readily understood that in forming the cut-away spaces a^2 , the web a' of the tie is sawed or slit and the metal between the slits is upset by suitable dies to form the offset portions a^3 .

55 Within each of the notches a^2 of the tie sets a tie plate B of metal of suitable thickness. In the construc-

tion shown in Figs. 1 to 5 of the drawings, each of the tie plates B is formed upon its inner and outer edges respectively with the reverted flanges b and b' , these flanges being separated from the base or body of the tie 60 plate B a sufficient distance to receive the base flanges c of the railway rail C. In order to securely hold the tie plates B in position upon the ties, each of these plates is formed with one or more shoulders or projections adapted to engage with the web a' of the tie. In 65 the form of the invention shown in Figs. 1-5 of the drawing, each tie plate B is formed at its side with a slot b^3 , the shoulders or projections b^4 at each side of these slots b^3 serving to engage the web a' of the tie when the tie plate is in position for use. 70

In order to enable the tie plate to be set in position for use, and interlocked with the tie and with the rail base, each tie plate after being passed beneath a rail, is turned to an angle of say, about 45°, as shown at the right-hand side of Fig. 1 of the drawing, so that the base flanges c 75 of the rail may drop between the up-turned flanges b and b' of the tie plate B, after which the tie plate B is turned from the position shown at the right-hand side of Fig. 1 to the position shown at the left-hand side of Fig. 1, when the flanges b and b' of the tieplate overlap the 80 base flanges c of the rail, and the notches b^3 of the tie plate are in position to drop over and interlock with the web a' of the tie.

When it is desired to insulate the rail from its base, a sheet of indurated fiber or other insulating material D 85 is inserted between the tie plate B and rail C. As shown, the insulating sheet D is of substantially the same shape as the tie plate B, having flanges d that correspond with the flanges b and b' of the tie plate. It will be understood, of course, that in setting the tie 90 plate in position, the insulating sheet D will be placed within the tie plate B before the latter is connected to the rail and to the tie, as above described.

When the parts are in the position illustrated at the left-hand side of Fig. 1 of the drawing, they may be retained securely in such position by means of a fastener E similar in construction to the fastener illustrated in my hereinbefore mentioned Letters Patent. This fastener E extends diagonally beneath and from side to side of the tie A and has its ends bent upwardly and 100 inwardly, the extreme upper ends e of the fastener being adapted to be bent over the flanges b and b' of the tie plate as clearly shown in Fig. 1 of the drawing.

From the foregoing description it will be seen that by forming the tie A with offsets a^3 that extend upon both 105 sides of the web a' , a broad and firm bearing for the rail is afforded upon each side of the web of the tie. It will also be seen that inasmuch as the tieplate B is interlocked with the base flanges c of the rail, and engages or interlocks with the web of the tie plate, all danger of the shifting of the tie plates, longitudinally or otherwise, is avoided. Moreover, the tie plates B being somewhat

- broader than the base flanges *c* of the rails *C*, the tie plates securely hold the rails out of contact with the tie and thus enable the insulating sheets to effectively perform their function of insulating the rails from the ties.
- 5 It is obvious that the precise details of construction above set out may be modified without departure from the spirit of the invention; and that features of the invention may be employed without its adoption as an entirety. Thus, in Figs. 6-8 of the drawing, I have 10 illustrated a modified form of the invention, the most important feature of this modification being the provision of plates or legs *b*⁶ which depend from the edges of each of the tie plates *B* opposite the reverted flanges *b* and *b'*. These depending plates or legs *b*⁶ extend 15 down to and rest upon the base flanges *a* of the tie *A* and thus effectively serve to guard against any possibility of the tie *A* turning, incident to any inequality in the ballasting of the road-bed beneath the tie. The tie-plate shown in Figs. 6-8 of the drawing is provided at 20 each side with a single offset or shoulder *b*⁴ adapted to engage or interlock with the web *a'* of the tie, when the tie plate is in position for use. The tie plate shown in Figs. 6-8 may be held in position by a retainer *E*, such as before described, and, it will be understood that an 25 insulating sheet *D* is inserted between the tie plate and the rail base before the tie plate is placed in position. The employment of the depending plates or legs *b*⁶ I regard as highly advantageous, although, as shown in Figs. 1-5, a successful construction of the tie plate may be 30 formed without them.
- Having thus described my invention, what I claim as new, and desire to secure by Letters Patent, is:—
1. A support for railway rails, comprising a metal tie having a vertical web formed at its top with cut-away 35 spaces and with expanded parts or flanges integral with the web and extending at each side of the web at the base of said cut-away spaces.
2. A support for railway rails, comprising a metal tie having a vertical web formed with cut-away spaces at its upper edge and tie plates resting upon said web and set within said cut-away spaces and flanged to engage the base of the rail. 40
3. A support for railway rails, comprising a metal tie having a vertical web provided at its upper edge with cut-away spaces, tie plates resting upon said web and set within said cut-away spaces and having shoulders interlocking with said web and having integral flanges oppositely disposed to interlock with the base of the rails. 45
4. A support for railway rails, comprising a tie having a vertical web provided with cut-away spaces at its upper edge, tie plates set within said cut-away spaces and having oppositely disposed upturned flanges to engage the base of the rails, said tie plates being broader than the base of the rails and being interlocked with the web of the tie. 50
5. A support for railway rails comprising a metal tie having a vertical web provided at its upper edges with cut-away spaces, tie plates set within said cut-away spaces and having centrally disposed laterally projecting ears or flanges to interlock with the web of the tie, said tie plates being formed at their opposite ends with upwardly turned integral flanges to overlap the base flanges of the rails. 55
6. A support for railway rails comprising a tie plate provided at each end and at each edge with an upwardly turned flange to engage the base flanges of the rail and provided at opposite corners with depending flanges adapted to extend to the base flanges of the tie. 60
7. A support for railway rails, comprising a tie plate provided at its ends with oppositely disposed, reverted flanges to engage the base flanges of the rail and provided with depending plates or legs to rest upon the base portions of the tie. 70
8. A support for railway rails, comprising a tie plate provided at its ends with oppositely disposed, reverted flanges to engage the base flanges of the rail and provided also with shoulders to interlock with the tie and hold the tie plate against longitudinal movement and with depending legs or plates to rest upon the tie. 75
